DESIGN FOR A NETTED TEXTILE FABRIC OR SIMILAR ARTICLE

Edmond P. Bixer, New York, N. Y.

Application February 8, 1940, Serial No. 90,123

Term of patent 7 years

To all whom it may concern:

Be it known that I, Edmond P. Bixer, a citizen of the United States, resident of Manhattan, in the county of New York and State of New York, have invented a new, original, and ornamental Design for a Netted Textile Fabric or Similar Article, of which the following is a specification, reference being had to the accompanying drawing, forming part thereof.

The figure is a plan view of a netted textile fabric showing my new design.

I claim:

The ornamental design for a netted textile fabric or similar article, substantially as shown.

EDMOND P. BIXER.
